UNITED STATES PATENT OFFICE.

ADOLPH P. SCHREMP, OF UTICA, NEW YORK.

FASTENING DEVICE FOR UNDERGARMENTS.

1,018,009.

Specification of Letters Patent.

Patented Feb. 20, 1912.

Application filed October 4, 1911. Serial No. 652,893.

To all whom it may concern:

Be it known that I, ADOLPH P. SCHREMP, of Utica, in the county of Oneida, in the State of New York, have invented new and useful Improvements in Fastening Devices for Undergarments, of which the following, taken in connection with the accompanying drawings, is a full, clear, and exact description.

10 This invention relates to takeup means for garments and pertains more particularly to underwear in which it is desired to change the size about the waist.

15 The object of my invention is to produce an efficient, durable and inexpensive means by which the circumference of garments may be readily and easily increased or diminished.

20 Other objects and uses will appear in the following description:

In the drawings:—Figure —1— shows my takeup means partially attached to the rear portion of an undergarment, including the upper and circumferential band thereof. 25 Fig. —2— shows a similar portion of a garment with any takeup device in position on the garment as worn.

To accomplish my purposes, I secure to the upper band of the garment a reinforced 30 strip of cloth —1— having button apertures —2— therein. One end of this strip is fastened to the inside of the garment band in any suitable manner as by stitching. I have shown it sewed thereto along the line 6—6. 35 The said strip then crosses the opening

—9— customarily existing in such garments, and is passed through the aperture —3— in the garment band. It is then lapped backward and again passed inside the garment across the opening —9— and through the 40 aperture —4— until one of the button holes or apertures —2— is in position to be placed over a button —5—.

It will be readily seen that the amount of takeup depends upon which of the apertures 45 —2— is used, and in connection with which button. I have shown but two apertures and two buttons, but it is apparent that more buttons or more apertures may be used without departing from the spirit of my invention. 50

What I claim is:

In combination with an undergarment divided through a portion of the rear side and provided with slits therethrough at opposite sides of the division, a strap attached to the garment some distance from the division beyond the slit at that side and extended across the division and through the other slit and returned through the division 60 and through the first named slit and attached to the garment. 55

In witness whereof I have hereunto set my hand on this 12th day of September 1911.

ADOLPH P. SCHREMP.

Witnesses:

EUGENE A. THOMPSON,
E. F. SPEARING.
